UNITED STATES PATENT OFFICE.

AUGUST G. SANDMAN, OF BALTIMORE, MARYLAND.

DRAFT RIGGING.

1,426,221.

Specification of Letters Patent. Patented Aug. 15, 1922.

Application filed July 20, 1920. Serial No. 397,778.

To all whom it may concern:

Be it known that I, AUGUST G. SANDMAN, a citizen of the United States, residing at Baltimore, in the State of Maryland, have 5 invented certain new and useful Improvements in Draft Rigging; and I do hereby declare the following to be a full, clear, and exact description of the invention, such as will enable others skilled in the art to 10 which it appertains to make and use the same.

The invention relates to draft rigging for railway cars, and more particularly to that class of draft rigging designed for application to passenger car underframes. 15 The primary object of the invention, generally stated, is to provide an interchangeable equipment suitable for either passenger or freight cars. To this end the principal feature of my invention consists in 20 providing novel means for pivotally connecting the coupler (of the freight car type) to a horizontal yoke.

Another feature of my invention consists 25 in interposing between the coupler and the cushioning mechanism therefor a plurality of members and in operatively connecting the coupler to one of said members and in pivotally connecting said member to the other member, and in connecting said members to the cushioning mechanism so as to 30 actuate the same.

There are other features of the invention 35 as will hereinafter appear from the more detailed description of the particular embodiment thereof which has been illustrated.

Referring to the drawings,—

Figure 1 is a plan view, partly in horizontal longitudinal section, of a draft rig- 40 ging and the associated portions of a car underframe.

Fig. 2 is a longitudinal central section of a passenger car underframe showing the invention applied thereto.

Fig. 3 is a horizontal longitudinal section 45 of a portion of the construction shown in Fig. 1 on a slightly larger scale.

Fig. 4 is a top plan view of the socket member to which the coupler is rigidly connected.

Fig. 5 is a side elevation of the same.

Figs. 6 and 7 are views, respectively, in top plan and side elevation of the spacer block which forms one of the principal features of my invention.

Throughout the specification and draw-

ings like parts are designated by like reference characters.

Before describing the embodiment of the invention herein illustrated in detail, it 60 might be well to point out that as a general rule there are two classes of equipment provided by every railroad, one commonly known as the freight equipment and the other as passenger equipment, the first being applicable only to freight cars and the 65 second applicable only to passenger cars. The reason for this distinction in equipment is two-fold. First, the difference in weight and number of cars employed in trains in 70 passenger service as compared with those in freight service, and second, the interchange rule which requires certain standard equipment to be employed in freight cars since freight cars are interchanged by the 75 different railroads, which rule does not apply to passenger cars, since passenger cars are, with few exceptions, run exclusively on the lines of each individual railroad.

The differences above set forth between 80 passenger and freight equipment require each railroad to keep on hand different repair parts of different kinds of equipments, resulting in increased cost of maintenance and duplication of parts which cannot be 85 interchangeably used. It will be apparent to those skilled in the art from the detailed description of the invention as hereinafter set forth that I have obviated this objection and have provided interchangeable 90 equipment suitable for either freight or passenger cars.

In the drawings, the coupler 1, which is of the ordinary freight type, is provided with a stem 2 which fits between and is 95 rigidly connected to a pivot block or socket member 3 by means of a key 4 which is adapted to pass through aligned slots in the jaws 5 of the socket member and through the usual key slot 6 provided in the coupler 100 stem 2. The socket member extends rearwardly of the coupler and is pivotally connected to a spacer block 7 by means of a pintle 8. The said block 7 is provided with a concave face 9 struck on the center of the 105 pintle 8, which is adapted to engage with the rounded end 10 of the socket member 3 to provide an adequate bearing and to relieve the pintle 8 of shear strain under buffering loads. In rear of the said curved 110 face 9 the block 7 is provided with a transversely extending slot 11 through which the

key 12 is adapted to pass, the said key extending through slots 13 in the arms 14 of the yoke, through slots in the cheek-plates 15, and through corresponding slots formed 5 in the sills 16. In rear of the slot 11 the block 7 is provided with a bearing face 17 in which may be a central opening 18 to receive the lug 19 of the follower 20. Extending from the upper and lower faces 10 of the block 7 is a pair of wings 21 which extend laterally of the upright side walls of the block 7 and are adapted to fit between the inner faces of the wear plates 22 which are connected to the inner faces of 15 the sills 16. These laterally extending wings 21 are adapted to engage the upper and lower faces of the block or socket member 7 and form a broad bearing to relieve the pintel 8 of strain caused by the drooping of 20 the coupler and the engagement of the side edges thereof with the wear plates 22 prevents any angling of the block 7 with reference to the yoke arms 14 or the sills 16.

A second key 23 is adapted to extend 25 through the slot in the follower 20, through registering slots 24 in the yoke arms 14, and through the slots 25 in the cheek-plates 15. The arrangement of cheek-plates, transversely extending keys and the slotted fol- 30 lower block is of the well known Farlow type of construction and need not be further described.

The yoke arms 14 are connected adjacent their inner ends by the transversely extending member 14^a, which is preferably formed 35 integral with the said yoke arms. Said member is adapted normally to engage the transversely extending web 26 of a back stop 27 which is interposed between and connected 40 to the adjacent sills 16 by means of the rivets 28. The said back stop 27 is preferably provided on its forward face with lugs 29 which lie on opposite sides of the yoke arms 14. The said lugs may be provided with laterally 45 extending lips or flanges 30 adapted to underlie the yoke arms 14 and form a support therefor. Interposed between the follower 20 and the ordinary form of flat follower 31 which engages the rear member 14^a of the 50 yoke, is a cushioning unit which is here shown as a combined friction and spring cushioning mechanism 32 of a well known type. It is to be understood that the particular form of cushioning mechanism here 55 shown is merely illustrative, and that other forms of cushioning mechanism may be employed if desired.

Referring now to Fig. 2, it will be observed that there is therein illustrated the 60 ordinary passenger platform 33, a platform buffer 34, a cover plate 35, a platform end sill 36 from which depends a carry iron 37 which may be of any desired conformation. The recess between the platform end sill 36 65 and the casting 38 is adapted to receive any

buffer cushioning mechanism (not shown). This recess is closed at the bottom by the plate 39, and to the lower face of the said plate 39 I connect, preferably by the rivets 40, a guide member 41 which is adapted to 70 overlie the pintle 8 and prevent the same from working upwardly. The wide bearing formed by the lower pair of wings 21 of the block 7 is adapted to rest upon a carry iron 42, clearly shown in Fig. 2, the said 75 carry iron being preferably connected at its side edges to the adjacent portions of the sills 16, and a second carry iron 43 may be provided, the said carry iron being adapted to underlie the rearward portion of the 80 cushioning mechanism 32 and form a support port for the same.

In passenger equipment it is desirable to permit a much greater angling of the coupler than in freight equipment, and by my 85 invention I have provided means whereby the coupler may swing laterally to the desired extent without interference and without contacting the side members of the yoke, and by providing a block or member, such 90 as the member 7, which is maintained in alinement with the yoke arms and which has a circular surface against which the rear end of the pivot block or socket member 3 abuts, it will be readily apparent to those skilled 95 in the art that all buffing strains will be transmitted from the coupler to the block 7 centrally thereof, and there will be no tilting action of the follower block 20 with reference to the cushioning mechanism. Under 100 buffing action the coupler 1, the socket member 3 and the block 7 will slide rearwardly independently of the yoke, forcing the block 20 rearwardly of the yoke and causing a compression of the cushioning mechanism, the 105 cushioning mechanism and yoke being held stationary by reason of the contact with the back stop 27. On a forward movement of the coupler, the coupler, the socket member and the block 7 and yoke all move outwardly 110 with reference to the car sills and the follower 20, the follower 20 being held from forward movement by the engagement of the key 23 with the stops provided on the cheek-plates 15.

Having now described my invention, what I claim and desire to secure by Letters Patent is:—

1. In a draft rigging, the combination with a yoke, of a block slidably connected thereto and adapted to engage the cushioning mechanism of the draft rigging, a coupler and means interposed between the said coupler and the said block and pivotally connected to one of said members for transmitting draft strains from the coupler to the said yoke.

2. In a draft rigging, the combination with the car sills, of cushioning elements connected thereto, means for compressing 130

- 5 said cushioning elements in one direction, a block slidably connected to said means and adapted to engage the cushioning elements, a coupler and separate means for connecting 45
5 said block to the said coupler, said block being movable longitudinally with the said coupler.
- 10 3. In a draft rigging, the combination with the car sills, of a yoke, a transversely extending key passing through the said yoke and adapted to operatively connect the said yoke to the said sills, a coupler and a block slidably connected to the said yoke, and means for pivotally connecting said coupler 50
10 to the said block.
- 15 4. In a draft rigging, the combination with a horizontally arranged yoke, of a follower block positioned between the arms of the said yoke, a second block adapted normally to bear against said follower, a key connecting said last named block with the said yoke, a coupler, and means for pivotally connecting said coupler to the said yoke, said means comprising a member rigidly 60
15 connected to the coupler and pivotally connected to said last named block.
- 20 5. In a draft rigging, the combination with a horizontally disposed yoke, of a block positioned between the arms of the 65
20 said yoke, a key slidably connecting said block and yoke, and means interposed between the coupler and said block and pivotally connected to the latter for uniting said coupler and yoke.
- 25 6. In a draft rigging, the combination with a horizontally disposed yoke, of a coupler and means for pivotally connecting said coupler and yoke, said means comprising a block slidably connected to the 70
25 said yoke, and an extension member, said
- member being provided with a socket at one end to receive the coupler stem and furnished at the opposite end with lugs which are adapted to pivotally engage the said block.
7. In a draft rigging, the combination with a horizontally disposed yoke, of a coupler and means for pivotally connecting said coupler and yoke, said means comprising a block slidably connected to the said yoke, and a member provided with a socket at one end to receive the coupler stem and pivotally connected at its opposite end to the said block. 75
8. In a draft rigging, the combination with a horizontally disposed yoke, of a block positioned between the arms of the said yoke, a key for operatively connecting said block to said yoke, means on the said block adapted to extend on opposite sides of the said yoke arms, said means being adapted to engage a stationary portion of the car under-frame, and means for pivotally connecting the coupler to said block. 80
9. In a draft rigging, the combination with the car sills, of a horizontally disposed yoke, a plurality of transversely extending keys passing through said yoke and adapted to operatively connect the said yoke to the said sills, a coupler and means interposed between the coupler and one of the said keys for pivotally connecting the coupler to said yoke, said means including a plurality of members, one of said members being slidably connected to the said yoke by means of another of said transversely extending keys. 85

In testimony whereof I affix my signature.

AUGUST G. SANDMAN.
